UNITED STATES PATENT OFFICE.

RICARDO GRASES RIERA, OF BARCELONA, SPAIN.

SAFETY ATTACHMENT FOR RAILWAY-CARS.

SPECIFICATION forming part of Letters Patent No. 409,707, dated August 27, 1889.

Application filed March 8, 1889. Serial No. 302,553. (No model.)

To all whom it may concern:

Be it known that I, RICARDO GRASES RIERA, a subject of the King of Spain, residing at Barcelona, Province of Catalonia and Kingdom of Spain, have invented certain new and useful Improvements in Safety Attachments to Railway-Cars, of which the following is a specification, reference being had to the accompanying drawings.

10 This invention relates to devices for clearing the rails of railway-tracks of obstructions by devices attached to the car-body; and it consists of the novel devices and combinations of devices hereinafter described and specifically claimed.

In the accompanying drawings, Figure 1 represents a side elevation of one end of a car having my improvement, and Fig. 2 a longitudinal vertical section of the same. 20 Fig. 3 is a plan of the car-axle and of the brushes, with the connecting machinery parts for driving the brushes and starting and stopping the movement of the same. Fig. 4 is an elevation of the axle and driving gear-wheel thereon; and Fig. 5 is an elevation, on an enlarged scale, of one of the brush shaft-hangers.

Corresponding letters of reference in the several figures of the drawings designate like parts.

A denotes one of the car-axles, having mounted car-wheels B and being journaled in boxes C of the car-body D. Forward of this axle A are pivoted in hangers E, also secured 35 to the car-body D, the journals of a shaft F, having rigidly mounted two circular brushes G, to be in line with car-wheels B.

Upon axle A is mounted a pinion H, and forward of this pinion H is pivoted between 40 two hanger-bearings a another pinion I, having cranks b to the opposite ends of its shaft, which cranks are placed in a relative rectangular position, and the shaft F having formed cranks c in about its middle, also on a relative 45 rectangular position and in line with the cranks b of pinion I. Each crank b is connected with a crank c by a pitman d, whereby the rotation of axle A is transmitted to pinion I and again to shaft F in a reversed direction.

50 The pinion H being loosely sleeved and feathered upon axle A, to allow lateral shift-

ing, its hub has an annular groove engaging the forked arm j of a rack-bar J, horizontally and transversally secured under the car-body in guide-brackets f, to slide therein, and below 55 this rack-bar J is pivoted in hanger-boxes g a shaft L, having mounted a pinion m, the teeth of which engage the teeth of the rack-bar J in a manner that the rotation in one direction or another of the shaft L will move 60 the rack-bar J to shift the pinion H into or out of gear with pinion I. The forward overhanging end of shaft L has mounted a small miter-wheel h, engaging with a miter-wheel i of a standard-shaft M, pivoted against the 65 platform dash-board of the car and provided with a hand-wheel K to its top for the conductor or driver to start or stop the movement of the brushes G.

The hangers E have slots e for the journals 70 of shaft F to enter, which slots e are curved to be concentric with pinion I. With raising or lowering said shaft F it will always be the same distance from pinion I, and inside of these hangers E a bar n for supporting the 75 shaft F is carried on two screw-rods o, secured between top and bottom lugs of hanger E, to be turned by means of a wrench, said screw-rods o being tapped through the ends of bar n, that with turning the same in one 80 direction or another will raise or lower the bar n and therewith the shaft F, that the brushes G may be adjusted to touch the rails as they become smaller from wearing. In communication with the curved slot e, each 85 hanger E has a notch p, in which the shaft F may be supported while the brushes G are not to be used.

It will be readily seen the herein-shown device will clear the rails from snow or other 90 obstructions by throwing the same in a forward direction.

In place of the pitman-connection between pinion I and shaft F, an endless chain or any other well-known device may be used, and a 95 shaft F, with brushes G, may be thus attached under each end of the car, one or the other to be used as the car may be moved in either direction.

What I claim is—

1. The combination, with a car, of a shaft 100 pivotally suspended forward of the wheels

thereof, and carrying circular brushes driven from the car-axle to rotate in a reverse direction by two pinions, the one mounted upon the axle to be laterally movable thereon for 5 shifting it in and out of gear, substantially as set forth.

2. The combination, with a car, of shaft F, carrying circular brushes and being journaled in slotted hangers E and supported on bars n, 10 suspended on screw-rods o for vertical adjustment, and of means for driving such shaft F from the car-axle in a reversed direction, substantially as set forth.

3. The combination, with a car, of shaft F,

carrying circular brushes G and being driven 15 from a pinion I, meshing with a pinion H, sleeved upon the car-axle, and laterally moveable thereon by a rack-bar J, having fork j, and being operated by a shaft L, having pinion m, all substantially as set forth, to operate as specified.

In testimony whereof I affix my signature in presence of two witnesses.

RICARDO GRASES RIERA.
